S. B. BOOTY

REPRODUCER FOR TALKING MACHINES

Filed June 7, 1922

FIG. 1

FIG. 2.

Inventor:
Stuart Bertram Booty,
By Alfred S. —
U.S.A.

UNITED STATES PATENT OFFICE.

STUART BERTRAM BOOTY, OF DULWICH HILL, NEAR SYDNEY, NEW SOUTH WALES,
AUSTRALIA.

REPRODUCER FOR TALKING MACHINES.

Application filed June 7, 1922. Serial No. 566,462.

To all whom it may concern:

Be it known that I, STUART BERTRAM Booty, subject of the King of Great Britain and Ireland, residing at 33 Barnesbury 5 Grove, Dulwich Hill, near Sydney, New South Wales, Australia, have invented certain new and useful Improvements in Reproducers for Talking Machines, of which the following is a specification.

10 This invention relates to sound-reproducers for talking machines which are operated with either disc records or cylindrical records.

The reproducer needle is set in a socket 15 in a platform the ends of which rest on two cone points which are set far apart on the sound box casing so that the platform will be freely movable in the direction of the normal oscillation of the needle and stylus; 20 said platform carries a transversely disposed leaf spring, the ends of which extend laterally of the length of the platform at either side of it and are constrained towards the sound box casing so as to hold 25 one end of the platform down on the cone point below it, by means of adjusting screws having cork cushion washers under their heads. A soft mica diaphragm is fitted in the sound box, and a stylus bar, the butt of 30 which is fixed in the platform is attached at its operative end to the centre of the diaphragm. The novel feature in the invention is the fitting of a long leaf spring transversely across the platform, with its 35 ends extended at either side of it and separately adjustable for tension by means of cushioned screws.

On the accompanying drawings Figs. 1, 2 and 3 are detailed views of a reproducer 40 according to my invention, respectively in side elevation, bottom plan, and end elevation, arranged for operation with records having laterally corrugated grooves.

The reproducer comprises a flat cylindrical casing 10 fitted with a bezel ring 11 arranged for compressing the packing rings 12-12 about either edge of the soft mica diaphragm 13. The neck 14 of this box is adapted to be set on the fore end of the tone 45 arm in the usual way. The lower part of the reproducer body is flattened as shown at 16, and two cone points 17 at the extreme ends of the flat are provided to form resting points for the platform 18. The plat- 50 form is retained resting on the points 17

by a helical spring washer 19 located under the head of a screw 20, which is driven into a tapped hole in the body of the reproducer. The needle socket 21 is centrally disposed on the platform 18 about midway between the cone points 17. 23 is a binding screw for fixing the reproducer needle 24 in the socket 21. 25 is the stylus arm, which, as usual, is connected to the centre of the diaphragm 13. The end of the platform 18 distant from the holding screw 20 is slotted horizontally and a tensioning leaf spring 26 set in the slot and sweated therein to form a T-head across the platform. It is important that the attachment of this spring to the platform shall be extremely solid and that it shall not depend upon mere screw or rivet fastenings in which local vibration might occur.

The leaf spring 26 is of considerable 75 length, being nearly the total length of the platform. The length of the platform is about half the diameter of the diaphragm. The leaf spring 26 is secured back to lugs 28-28 formed on the reproducer casing by 80 means of tensioning screws 29-29 passed through holes in the ends thereof; these screws are set by means of back nuts 30-30. Under the screw heads 29 cork compression washers 31 are inserted. When the 85 screws 29 are driven home these washers are compressed, they serve the purpose of preventing rattling of the spring 26 against the screw heads 29. The screws 29 are set to establish transverse tension through the 90 spring on the needle and stylus mounting to stress the diaphragm inward and outward or to set it neutral i. e. without tension in either direction, the reproducer being set according to the usual practice so 95 that the needle subjected to vibration imposed by the grooves in the record, whether the grooves be of the lateral type or of the hill-and-dale type. The provision of a variable damper for the diaphragm which is 100 controllable so that the diaphragm may be left free to vibrate or may be constrained in either direction is an important result attained by my invention. The stylus arm 105 25 is a tapered knife blade, so formed to ensure maximum rigidity transversely of the diaphragm and maximum flexibility in parallel with the diaphragm. The long base afforded the platform 18 on the widely disposed cone points 17 and the rigidity of 110

the platform in the direction of its length minimizes transmission of vibrations through the needle and stylus bar in a direction parallel to the face of the diaphragm. The platform is, however, perfectly free for vibratory movement transversely of its length upon its cone point supporters, and its liberty to vibrate transversely and consequently the liberty of the diaphragm to vibrate is controllable by the adjustment of the tensioning screws 29.

The leaf spring 26 is preferably of phosphor bronze about 30 B. W. gauge in thickness, and when used with a diaphragm of about 2 inch diameter and proportioned thereto approximately according to the measurements deducible from the drawings, it procures a tensioning of the platform transversely to its length which is variable within extreme limits to accommodate it to the characteristics of particular records to secure satisfactory reproduction. It is how-

ever necessary that the reproducer diaphragm be constructed of soft mica. The desired quality and purity of sound is not otherwise obtainable, a substantial alteration in value being found when hard mica or other substance is used instead of soft mica.

I claim as my invention:

In a sound-reproducing device, a casing, a stylus bar, a platform carried by said bar, bearing members between said platform and casing, yielding means for holding one end of said platform against one of said bearing members, a spring extending transversely of and in contact with the other end of said platform for holding it against the other bearing member, and means for adjustably supporting the ends of said spring on said casing.

In testimony whereof I affix my signature.

STUART BERTRAM BOOTY.
